CLAIM

The ornamental design for a portable movie camera, as shown and described.

DESCRIPTION

FIG. 1 is a front and right side perspective view of a portable moving camera showing our new design with the view handle in the housed configuration;

FIG. 2 is a rear and left side perspective view of the portable moving camera with the view handle in the extended configuration;

FIG. 3 is a rear elevational view of the portable moving camera with the view handle extended toward the right;

FIG. 4 is a rear elevational view of the portable moving camera with the view handle extended toward the left;

FIG. 5 is a front elevational view of the portable moving camera with the view handle extended toward the right;

FIG. 6 is a left side elevational view of the portable moving camera shown in FIG. 1;

FIG. 7 is a right side elevational view of the portable moving camera shown in FIG. 1;

FIG. 8 is a bottom plan view of the portable moving camera shown in FIG. 1;

FIG. 9 is a top plan view of the portable moving camera shown in FIG. 1;

FIG. 10 is a left side elevational view of the portable moving camera shown in FIG. 2;

FIG. 11 is a right side elevational view of the portable moving camera shown in FIG. 2;

FIG. 12 is a bottom plan view of the portable moving camera shown in FIG. 2; and,

FIG. 13 is a top plan view of the portable moving camera shown in FIG. 2.
